UNITED STATES PATENT OFFICE

LLEWELLYN MARSH WILLEY, OF HOOSICK FALLS, NEW YORK, ASSIGNOR TO SPECIALTY INSULATION MANUFACTURING COMPANY, INC., OF HOOSICK FALLS, NEW YORK, A CORPORATION OF NEW YORK

HANDLE

Application filed November 7, 1928. Serial No. 317,781.

This invention relates to improvements in handles. More especially it relates to molded composition handles which are suitable for a variety of household and other uses, such as for electrical appliances, pots, pans, cutlery and tools, and for numerous other uses where a light, strong and durable handle is desired, or one affording insulation against heat or electricity.

It is among the objects of the invention to embody in such handles structural features making for economy in manufacture, providing important heat-insulating advantages, and attaining needed strength and durability with a minimum weight of material. And still another object is to reduce in number the operations required for complete manufacture of a handle, thus to expedite and simplify production and to lower production costs. It is moreover an important feature that the improved handles are adapted for ready and quick substitution for old or broken ones, and this by the housewife, or any person, without any particular mechanical skill.

These objects and results may be attained by molding the handle in two half-shell portions or sections, each constituting a longitudinal half of the complete handle, and each 30 half-shell formed with struts rising interiorly from the bottom of its cavity to the plane of cleavage, when half shells are put together, to make a complete local strut to take the compression of a screw that fastens the 35 handle to its utensil. The external configurations of the sections of handle are determined by the internal contour of the mold, which may be made as desired. The mold also may have means by which holes for 40 the fastening screws may be formed in the sections during the molding operation. The final product of the molding is such that no painting, enamelling or other like finishing operation is necessary, as a suitable coloring 45 agent may be embodied in the mass of material which is put into the mold, and the molding operation can impart a smooth and somewhat glossy finish, so that the molded product is ready for market after the simple operation of assembling the two halves.

In assembling, two halves come together with their internal struts abutting together, or clamping the tang of an implement between them. Thus internal solidity is provided at two or more locations along the handle. And the securing devices, preferably bolts, conveniently may extend through these solid portions to effect the double function of securing the handle sections together, and of securing the whole handle to the device on which it is to serve. Because of the half-shell form of the handle sections, hollows are provided within a completed handle, which are air pockets that tend to maintain the handle cool; contribute lightness, for handling; and save material in manufacture.

It is intended that the patent shall cover, by suitable expression in the appended claims, whatever features of patentable novelty exist in the invention disclosed.

In the accompanying drawing:

Figure 1 is an elevation, partly in section of one form of my improved handle as adapted for a coffee pot, pan cover, or other article;

Figure 2 is a plan of the same, with either portion removed on the cleavage 2-2, showing the internal structure which is common to both upper and lower portions of Figure 1;

Figure 3 is an elevation of a handle of the same shape but adapted for a different style of fastening to a flatiron or other article;

Figure 4 is a plan showing detail of one end of Figure 3;

Figure 5 is an elevation of a handle of similar shape but with modification adapting it for still a different style of fastening, as to a spoon;

Figure 6 is a plan showing detail of one end of Figure 5;

Figure 7 is an end elevation of Figure 3 or 5 in section on 7-7;

Figure 8 is the same on 8-8;

Figures 9 and 10 are end elevations of a modification of the form of either Figure 3 or 5; and are in section on planes similar to Figures 7 and 8 respectively.

Referring to the drawing, each handle

may comprise two shell sections 10, 12 assembled together to provide a cross-pillared hollow handle, split longitudinally, whose interior pillars comprise strut sections 14 in the form of bosses which coact in the assemblage to produce solid cross-walls at two or more locations along the handle. The walls 14 divide the hollow of the handle into a series of air-pockets 16, which are heat insulating when the handle is in use. And the clamping and attaching devices, such as the bolts 18, (Figure 10) may extend through these solid walls, thus applying their compression to the hollow handle where resistance to strains and stresses is greatest, and where it is in effect solid, as is illustrated, Fig. 10; with reference to another form.

According to the invention the handles are to be molded of some suitable composition material. Bakelite is an example of material which may be formed in the mold to constitute the handle. Synthetic rubber substitutes may likewise be used, of which colasta is an example, and other materials which can be condensed or formed by heat and pressure in a mold. With such material, and with molds arranged in gangs, it is practicable to produce a considerable number of completed handle sections at each single operation of the press.

30 A feature of industrial importance is that the handle sections come from the molds in finished form ready for simultaneous assemblage and attachment to the device on which the handle is to serve. This is accomplished by simple addition of coloring agents to the plastic mass prior to molding, and by the making of the mold with suitable smoothness or even gloss on its interior surface, to be imparted to the product molded therein.

40 Referring now to Figures 1 and 2 of the drawing, the handle there seen is particularly adapted for tea-urns, coffee-pots, stove doors and the like upright surfaces, and for lids, flatirons or other horizontal surfaced article. In this form the lower portion 12 of the handle is (as seen in Figure 1) formed, in the molding operation, with two exterior bosses or spacing arms 13 whose ends are adapted to abut against the upright side of 45 a coffee pot or a stove door; or against the horizontal top of a flatiron, and to be secured thereto by bolts, (not shown) each of which extends through an arm 13, in the hole 19, and through abutting internal struts 14 of the two half shells. Holes for the passage of these bolts may be formed when the two portions are molded, by cores in the molds. For this purpose there may be pins which 50 project into the mold at desired locations, 55 they serving as cores around which the plastic material is molded.

The form of handle seen in Figures 3, 4, 7 and 8 has the portion 12 of Figure 1 replaced by a portion 22 whose shape is identical with that of the portion 20 that replaces

10 A socket 21 at each end is formed by the coming together of faces which are slightly rebated in each portion, as molded. And a hole 29 is molded at each end for reception 70 of a bolt. Each socket 21 is adapted to receive a flat tang which may extend from a flatiron, the side of a pan, or the like. The tang may extend in axial direction into the end of the handle, or it may extend into a side of the handle at one end in the plane 75 of cleavage. And in either case a bolt can pass through the two portions of handle and through the tang to clamp the latter firmly between the same sort of struts 14 as in the handle of Figures 1, 2, which rise to the surface where force is to be exerted. In Figure 1 they rise into mutual contact. In Figure 3 the space for tang is between them.

80 A device suitable for fastening the handle to cutlery, tools and other implements is seen in Figures 5, 6, 7 and 8. In this case a single long socket 31 is provided by the same method as described for the slots 21 of Figure 3, and a single long tang may be clamped 85 between the sections 30, 32 by bolts passing through the two holes 38, one near each end 90 of the handle.

95 Preferably, in handles having sockets the sockets will be for the most part internal recesses, and will be apparent externally only at necessary points where tangs are intended to enter. An embodiment of this design is shown in Figures 9 and 10, where the tang space between portions 40 and 42 is 41; and outside of that the visible space between portions 100 is very thin, as at 43.

I claim as my invention:

1. A handle, comprising two hollow shell sections, comprising molded heat-insulating composition material of organic origin, 105 adapted to fit together and combined with screw means, penetrating both sections to hold them together; each of these shell sections having two interior medial bosses, one of which is located near each end of the handle, and each of which bosses stands opposed to a boss on the other section; and there being an orifice for a screw to pass through each 110 said pair of bosses and across the cleavage between shell sections with the boss material closely surrounding the screw, each of which screws secures the sections together and to the device on which the handle is to serve.

115 2. A handle, comprising two hollow shell sections adapted to fit together and combined with screw means, penetrating both sections to hold them together; the said sections comprising molded heat-insulating composition material of organic origin; one of these shell sections having interiorly two bosses, 120 each extending into the hollow from one of its shell side walls to the other, these two bosses being located respectively near the ends of the section; the other shell section 125 having like interior bosses opposed to those 130

of the first, and having exterior bosses constituting continuations of these said interior bosses; and there being an orifice for a screw to pass through all three of said bosses which
5 are in line, and across the line of cleavage of shell sections; with the boss material surrounding closely the screw which clamps the sections to each other and to the device on which the handle serves, thus extending from
10 the head of the screw, which is beyond the first mentioned section, to the said device for which the handle serves.

3. A handle, comprising two hollow shell-sections, of which one section has a pair of exterior tubular legs which are at their ends adapted for engagement with an article to be held by the handle, one leg being near each end of the handle; and each section has, interiorly of the handle, two abutment faces
20 for mutual engagement of the sections interiorly of the handle, these being at each of two separated locations along the handle, one of these abutments on one section registering with an abutment of the other section,
25 which said locations correspond to the said locations of exterior legs; there being an opening extending through the mutually registering faces at each said place of registering each said opening in turn registering with
30 the opening through one of said exterior tubular legs; and said registering openings being adapted to receive fastening means passing therethrough.

Signed at Hoosick Falls, New York, this
35 30th day of October, 1928.

L. MARSH WILLEY.
